CLAIM

The ornamental design for a lens for camera as shown and described.

DESCRIPTION

FIG. 1 is a top, front, left side perspective view of a lens for camera showing my new design;

FIG. 2 is a top, rear, right side perspective view thereof;

FIG. 3 is a top, front, right side perspective view thereof;

FIG. 4 is a front view thereof;

FIG. 5 is a rear view thereof;

FIG. 6 is a top plan view thereof;

FIG. 7 is a bottom plan view thereof;

FIG. 8 is a right side view thereof; and,

FIG. 9 is a left side view thereof.

The broken lines illustrate portions of the lens for camera and form no part of the claimed design.

1 Claim, 6 Drawing Sheets
